STOKER APPARATUS

Delmond L. Getz and Edward C. Lafferty, Springfield, Ohio, assignors to The Steel Products Engineering Company, Springfield, Ohio, a corporation of Ohio

Application November 14, 1949, Serial No. 126,962

8 Claims. (Cl. 236—73)

1

This invention relates to stokers and more particularly to a modulating type stoker system.

In the ordinary installation of a stoker, particularly the type employed in household heating plants and the like, it is customary to employ a thermostat or other heat sensitive element which controls the operation of the stoker so that it is either on, when the temperature to be controlled is below the desired value, or off when the temperature is above such value. While such controls are satisfactory from the standpoint of maintaining desired temperature conditions, it has been found that such a system is open to objection from the standpoint of smoking conditions, the smoking usually occurring upon the shutting down of the supply of fuel, because there is a concurrent stoppage in the supply of combustion air from the blower, such sudden shutoff frequently producing smoking.

In accordance with the present invention a heat sensitive control is provided which may be actuated either by the temperature in the space to be controlled, or by the pressure, as in a boiler for example, and which is of such character that it has a range of positions, varying from a high to a low demand for heat, as distinguished from a mere on and off position. This modulating control element is then associated with a stoker system incorporating a fuel and an air supply means in such manner that both the rate of supply of fuel and of the air are varied or modulated in accordance with the position of the heat sensitive control. Thus under cold weather conditions where a high rate of heat supply is necessary, the system produces a rate of operation of the fuel supply means which is correspondingly high. This is accompanied by a proportionate increase in the rate of introduction of combustion air. As the demand for heat becomes less, the control modulates the action of the supply system, reducing, but without terminating, the rate of introduction of fuel and thereby maintaining a desired temperature condition with such lesser heat input. Concurrently the supply of air is reduced to the proper level corresponding with the reduced rate of fuel supply.

Normally this modulating control continues to function, the thermostat or heat responsive element providing for either increasing or decreasing the correlated rates of fuel and air supply, but without actually terminating such supplies, and hence effectively producing or eliminating the smoke condition referred to above and providing improved overall combustion, maintaining a more uniform depth of fuel bed, and resulting in higher overall efficiency.

The stoker system preferably employed is one

2

which operates on an intermittent basis, and this in turn is controlled by a cyclic time control member with the fuel being supplied intermittently for a greater or lesser part of each cycle of the device. Thus when the demand for heat is the greatest, the control may produce such feeding operation of the fuel substantially throughout the entire portion of the cycle; as the demand for heat decreases, the portion of the cycle during which the fuel supply continues is progressively reduced to a minimum, which minimum however is sufficient to keep the furnace in operation on a standby basis, thus assuring that it will be ready and in condition for a higher rate of operation whenever desired and without the complete shut down of fuel and air supply which had led to the undesirable conditions described above.

There is also preferably provided a manual control which can be used to override the automatic action of the system and to provide for terminating the fuel supply while continuing the flow of combustion air, when for example it is desired to allow all of the fuel in the furnace to burn out, either for shutting down the furnace, or for the necessary removal of clinkers, or the like.

It is accordingly the object of this invention to provide such a stoker system which is responsive to a heat condition to be maintained and which modulates the supply of fuel and air in correlated relation to each other and in accordance with the requirements for heat, while maintaining a continuity of operation and avoiding the objectionable smoking and other conditions associated with an abrupt and complete stopping of the operation.

Other objects and advantages will be apparent from the following description, the accompanying drawings and the appended claims.

Referring to the drawings—

Fig. 1 is a view in elevation with certain parts being broken away showing a stoker constructed in accordance with the present invention;

Fig. 2 is a view of the stoker at right angles to the showing in Fig. 1;

Fig. 3 is a detail view partly in section showing the damper control for regulating the supply of air;

Fig. 4 is a schematic layout in perspective showing the drive and control system in accordance with the present invention;

Fig. 5 is a view in vertical section through the gear casing of the device on the line 5—5 of Fig. 6 with parts shown in elevation;

Figs. 6, 7 and 8 are vertical sectional views on the lines 6—6, 7—7 and 8—8 of Fig. 5, respectively;

Figs. 9, 10 and 11 are sectional views on the lines 9—9, 10—10 and 11—11 of Fig. 8, respectively;

Fig. 12 is a view on an enlarged scale through the drive shaft of the stoker showing details of the control mechanism; and

Fig. 13 is a vertical detail sectional view through the manual control for positively terminating the operation of the stoker.

Referring to the drawings which disclose a preferred embodiment of the invention, the stoker is shown by way of illustration as having a main drive motor 10 serving as a source of power, which is enclosed within a casing 11 mounted upon the main gear casing 12. The motor has a drive pulley 14 which carries V-belts 15 that drive pulley 16 on the main driven shaft 17 suitably journaled in casing 12 on antifriction bearings 18. The shaft 17 extends through the gear casing and on its opposite end is directly connected to the rotor 20 of a sirocco type blower which operates in blower housing 22. The blower inlet is shown at 23 and is provided with a series of vanes 25 which are mounted for rotation on individual shafts 26 between relatively closed and open positions thus effectively throttling the inlet to the blower and providing for regulating the amount of combustion air.

The control responsive to the heat condition to be maintained is shown diagrammatically at 30 in Fig. 4 and is of suitable type to provide the desired modulating control, such as a variable electrical current flow, depending upon the heat condition to be maintained. Such control is electrically connected as shown at 31 to an actuator 32 which is supplied with low voltage current by transformer 33 from power lines 34. The actuator is arranged so that its control shaft 35 rotates and thus rocks the sector 36 from one angular position to another, corresponding to the operation of control 30. In the arrangement illustrated in Fig. 4, the sector 36 is arranged to rotate in a clockwise direction in response to an increasing demand for heat. A suitable modulating control 30 and actuator 31 for use in the present system is a Minneapolis-Honeywell L-91 control with M904E Modutrol motor.

Connections are made from this actuator 32 to regulate both the air supply and the fuel supply and such supplies are varied in correlated relation with each other. Referring first to the mechanism for regulating the supply of air, a rod 40 is connected to a suitable point on sector 36 and at its opposite end to the lever 42, a series of apertures being formed in the lever in which the rod may be selectively positioned to secure a different amount of movement, depending upon the particular adjustment desired. Lever 42 is fixed to a pivot pin 44 rotatably supported in the wall of the gear casing 12.

A second rod 50 is also connected to lever 42 and at its upper end is pivotally connected to a crank 51 secured to shaft 52 rotatably mounted in bracket 53 which in turn is supported from the gear casing. The opposite end of shaft 52 is connected with a link 55 and this in turn operates through a link 56 to rotate crank 57 secured to shaft 58 rotatably supported in brackets 59. The opposite end of the shaft 58 carries a crank 60 connected to a link 61 which carries a lever 62 at its opposite end, lever 62 being connected to the shaft 26 of the damper in such manner that upon adjustment thereof, the damper will be caused to oscillate on the axis of shaft 26 between its open and closed positions. It will thus

be evident that in response to operation of the actuating sector 36, there will be a direct and corresponding adjustment in the setting of the damper, providing for opening the damper with increasing demand for heat and thus correlating the rate of air supply with the rate of fuel supply. It will be understood that the various linkages may be so adjusted as to obtain the precise movements of the damper for each setting of the actuator as desired to give a specific volume of air flow determined to be correct for that rate of fuel consumption.

The fuel is supplied to the combustion zone by means of a suitable conveyor, and for purposes of illustration the invention will be described with reference to a stoker arrangement adapted to withdraw solid fuel from a bin and feed it into a retort, such as the arrangement shown in Scholl Patent No. 2,364,166, assigned to the same assignee as this application. In such a system one fuel conveyor tube such as 65 provides for withdrawing fuel from the bin, under the action of an internal worm conveyor indicated at 66, the fuel being transferred in a transfer chamber 67 to a second fuel conveyor tube 68 having a similar conveyor worm 69 therein for feeding the fuel forwardly to the retort. The drive shafts of both conveyor worms 65 and 69 extend beyond the wall of the chamber 67 and on their overhanging ends carry drive sprockets 70. Chains 71 connect each sprocket 70 to driving sprockets 72 and are protected by covers 73, such driving sprockets being mounted upon opposite ends of the drive shaft 74, suitably journaled in the gear casing. Thus upon the rotation of such shaft 74 a corresponding and identical rotation of the two conveyor flights is produced, with consequent supply of the fuel from the bin, or other reservoir or fuel supply chamber as the case may be, forwardly and into the retort.

In order to provide for the desired intermittent but controlled operation of shaft 74 and the corresponding operation of the worms to supply the solid fuel, the mechanism in gear case 12 is provided as follows. Shaft 17 carries a worm 80 which drives the worm gear 82 loosely mounted on shaft 74. The gear has a laterally extending hub 82a which is pinned as shown at 83 to the hub 84 of a cam 85, the cam therefore rotating freely on shaft 74, being directly driven from gear 82.

A follower in the form of a roller 87 rides against the surface of cam 85 and is rotatably supported by a pair of rocker arms 88 suitably mounted on pivot shaft 90 journaled in the gear casing 12 by suitable antifriction bearings 91 (Fig. 9).

Shaft 90 has an additional arm 93 extending radially therefrom and a cross pin 94 extends from the two arms 88 to arm 93, furnishing a support for the connecting links 95 which are carried on pin 94 and held in proper spaced relation thereon by means of cotter pins 96. A projecting pin 97 extends from the lower end of arm 93 and is formed to receive tension spring 98 which normally acts to swing shaft 90 about its axis and thus to maintain roller 87 in continuous riding contact against the surface of cam 85.

Connecting links 95 extend upwardly to a main feed pawl 100 which is rotatably mounted upon pivot pin 101 which in turn is carried by a pair of radius plates 102 loosely mounted on the hub of a main drive ratchet wheel 105. The pawl is in such position that when it is moved in a counterclockwise direction (Figs. 7, 8 and 12) under

the camming action of the rocker arm assembly, it will drive the ratchet wheel 105 also in a counterclockwise direction. The ratchet wheel has an extended hub 106 through which there extends a shear pin 107 forming a rupturable driving connection with shaft 74. Thus rotation of the ratchet wheel 105 effects corresponding direct driving movement of shaft 74 up to the limiting strength of the shear pin which is included for safety purposes. As shown in Fig. 5 the shaft 74 is directly journaled at one end in antifriction bearing 108 carried by casing 12, and at its other end is supported in sleeve 109 which in turn is journaled in antifriction bearing 109 carried by the casing. A retaining pawl 110 pivotally mounted on pin 111 in the casing 12 and normally urged toward engaging position by weighted end 112 serves to prevent backward rotation of ratchet wheel 105.

A timing ratchet wheel 115 is mounted for free rotation on the hub 106 of the main ratchet 105 and is arranged to be driven by a pawl 116 carried on the pin 101 and hence movable in corresponding timed relation with the rocker arm 88 under the driving action of the cam 85. A retaining pawl 117 is mounted on pin 111 and arranged opposite the teeth of pawl 115 to prevent backward rotation thereof, such pawl being suitably weighted as shown at 118 to bias it toward engaging position. Timing ratchet wheel 115 may thus operate independently of the main ratchet 105, and is formed with an axially extending hub portion 120 which is shaped as shown in Fig. 8 to define a series of cam steps 121. Preferably these steps progress from a minimum to a maximum and back to the minimum position in a continuous series of relatively small increments.

A cam follower in the form of a roller 125 (Figs. 4 and 12) is arranged to ride the cam surface 121, the roller being carried by a rocker arm 126 supported on the positioning lever 127 by means of pin 128. Lever 127 is secured to the pin 44 and oscillates with such pin, thereby swinging the roller 125 closer to or farther away from the surface of cam 121. Rocker arm 126 is connected through a floating pivot 130 with a link 131 and through it with operating lever 132. Lever 132 is secured to and causes rotation of a sleeve 133 suitably journaled in a portion of casing 12 (Fig. 13). The sleeve is normally biased by means of a torsion spring 135 acting against stop pin 136 in the direction to cause the lever 132 to swing in a counterclockwise direction as shown in Fig. 12. A shaft 137 extends through sleeve 133 and its inner end provides a pivot for loosely receiving an interference arm 138 which projects radially therefrom and toward and under a laterally projecting tongue 139 on the main drive pawl 100.

Sleeve 133 has a projecting finger 140 fixed thereto which is arranged to engage pin 141 carried by interference arm 138 so that upon rotation of sleeve 133, the interference arm will be raised to lift pawl 100 out of driving engagement with ratchet wheel 105, or lowered to establish and render such drive operable. A second finger 142 is likewise formed on sleeve 133 in position to receive the pin 141 when the interference arm is swung away to a clearance position, preventing excessive travel thereof.

When the interference arm 138 is in position to raise the main drive pawl, causing it to rock about its pivot shaft 101, such pawl is retained in the clearance position in which, notwithstanding the rocking movement of the rocker arm 88 and of the radius plates 102, it no longer has driving engagement with the teeth of the main drive ratchet 105. This prevents the transmission of any driving power to the worm drive shaft 74 as long as this condition exists. However in response to the lowering of the interference arm, the main drive pawl 100 is then allowed to engage the teeth of the drive ratchet 105, providing for establishing the driving connection to the worm drive shaft 74.

The operation of the system takes place as follows. With the drive motor 10 in operation, shaft 74 is driven at a continuous and substantially constant rate of speed, and this in turn produces rotation of the main worm gear 82 and of cam 85. In response to rotation of cam 85, rocker arm 88 oscillates about its pivot shaft 90, and this in turn through the action of the connecting links 95 produces a corresponding oscillatory movement of the radius plates 102 and the pawl assemblies carried thereby. This includes the main drive pawl 100 and the timing cam pawl 116. Since there is no interference at any time with the driving action of pawl 116, such oscillatory movement produces a corresponding step by step advance in the rotation of the timing ratchet 115, and a similar or step-by-step movement of the timing cam 121.

Under the action of the biasing spring 135 the sleeve 133 and its supporting finger 140 tend to be shifted in a counterclockwise direction as shown in Fig. 12, with the result that the finger 140 picks up the pin 141, and causes interference arm 138 to be lifted, thereby engaging the projection 139 on pawl 100, raising it to and retaining it in its inoperative position. This interrupts or disables the drive to the worm operating shaft 74, but does not interfere with the continuous step by step rotation of the timing cam. As the timing cam rotates, at some point in its rotation it will engage the roller 125, causing that roller to rise, thus rocking lever 126 about pivot 128, which in turn causes the motion to be transmitted through link 131 and lever 132, rocking lever 132 in a clockwise direction and thus overcoming the biasing action of spring 135. Such rotation of the sleeve results in the lowering of finger 140 and of interference arm 138, thus allowing the main drive pawl 100 to drop into driving relationship with the teeth of the main ratchet wheel 105. As long therefore as the cam engages roller 125, and thus retains the interference arm in withdrawn position, each successive step of movement of the rocker arm 88 will cause a corresponding driving engagement of the pawl with the ratchet 105, producing a corresponding step of rotary movement in shaft 74.

The particular point in the cycle of the timing cam at which the roller is engaged is determined by the setting of lever 127, and this in turn is controlled through operation of lever 42 and the positioning of the sector 36 of the actuator. As the actuator changes its position in response to the demand for heat, lever 127 is rotatably adjusted and this produces a corresponding shifting in the position of roller 125, causing it to be engaged either earlier and thus for a greater portion of the cycle, or later and thus for a lesser portion of the cycle of rotation of the timing cam. In this way the number of strokes of advance movement of the worm drive shaft 74 which occur during each timing cycle may be varied, a suitable control providing twenty-one positions on the cam and thus making it possible to vary the rate of feed over a range varying from

one step per revolution to twenty-one steps and hence substantially continuously throughout the operation of the system.

As the rate of fuel supply varies under control of the modulating control, the actuator 32, working through connections 48, 42, 50 and the related linkage, provides for a corresponding adjustment in the setting of the vanes 25 and thus regulation of the supply of combustion air is maintained in completely correlated relation with the supply of fuel.

In some cases it is desirable to provide for manual control of the stoker in order to be able to shut off the supply of fuel completely while allowing the motor drive to continue for the purpose of supplying combustion air and thus completing the combustion of the fuel already in the retort. For this purpose the control illustrated in Fig. 13 is incorporated, and includes a manual control member 150 in the form of a lever which carries a yieldable detent 151 to yieldably retain the arm in either the manual or automatic position. In the automatic position, the operation takes place in the manner already described. However when the handle is adjusted to the manual or off position, the shaft 137 is rotated within sleeve 133 and in so doing a finger 152 thereon is caused to engage beneath pin 141, causing the lifting of the interference arm to a continuing interference position. Thus regardless of the position of roller 125, which would otherwise lower the interference arm at some point in the timing cycle, the interference arm remains in its raised position, thus completely disabling the drive and preventing the rotation of shaft 74. Meanwhile the drive motor continues to operate and thus the blower continues to supply combustion air, allowing complete combustion of such fuel as remains upon the retort.

It will thus be seen that the invention provides a simple and highly satisfactory arrangement for continuous modulating control of the supply of fuel, providing for the intermittent operation of the fuel supply worms for a predetermined and variable portion of a timing cycle as required to bring about the proper rate of fuel supply. There is a corresponding operation and correlation of the rate of air supply from the blower so that proper modulated control of the air is likewise maintained, in order to establish and maintain the most efficient combustion conditions. The system thus assures the operation of the stoker at such a rate as to maintain a predetermined heat condition, and with a continuously varying rate of supply to meet the demand. There is no abrupt change in operation such as an on and off condition, and the objectionable smoking and inefficient combustion associated with such type of operation are effectively avoided.

While the form of apparatus herein described constitutes a preferred embodiment of the invention, it is to be understood that the invention is not limited to this precise form of apparatus, and that changes may be made therein without departing from the scope of the invention which is defined in the appended claims.

What is claimed is:

1. A stoker system operable to provide a variable rate of fuel supply in a selected number of uniform feeding strokes of a fuel feeding member during an interval and under control of a modulating device responsive to a heat condition to be maintained, comprising a main drive ratchet connected to said fuel feeding member

for operation thereof, a main drive pawl adapted for operating engagement with said main drive ratchet, means for continuously oscillating said main drive pawl to produce a series of uniform feeding strokes of said feeding member when said pawl is in engagement with said main drive ratchet, an interference arm for retaining said main drive pawl out of driving engagement with said main drive ratchet, a timing cam rotatable separately from said main drive ratchet and having a series of steps thereon ranging from a minimum to a maximum in small increments, means operated by said oscillatory means for producing uniform periodic advancing movements of said timing cam in response to each said oscillatory movement, a cam follower, means actuated by said modulating control for adjusting said follower in predetermined position relative to said cam to be engaged by a portion of said steps in the course of the revolution thereof, and linkage connecting said cam follower with said interference arm to cause said interference arm to be withdrawn allowing said main drive pawl to engage said main drive ratchet during the period that said cam follower is raised by the steps of said cam.

2. A stoker system as defined in claim 1 in which the timing cam is advanced by a timing ratchet, and in which the means operated by the oscillatory means for advancing the timing cam includes an auxiliary pawl engaging said timing ratchet.

3. A stoker system as defined in claim 2 in which the timing ratchet and the main drive ratchet are mounted coaxially with each other.

4. A stoker system as defined in claim 2 in which said main drive pawl and said auxiliary pawl are carried on the same oscillating means.

5. A stoker system as defined in claim 1 in which the steps on the timing cam are arranged in a series which increases and then decreases through a uniform series of increments.

6. A stoker system as defined in claim 1 in which the interference arm is normally biased toward interfering position and is positively withdrawn in response to engagement of said cam follower with a step on said timing cam.

7. A stoker system as defined in claim 1 including means for regulating the air supply, and means operated by said modulating control for also actuating said air supply regulating means in coordinated relation therewith.

8. A stoker system as defined in claim 7 including a manual control for terminating the supply of fuel by said feeding member while continuing the air supply.
